PARACHUTE CARRIER

Chester J. Lucci, Max J. Lukas, and Edward J. Tusina, Wheeling, W. Va.

Application December 11, 1952, Serial No. 325,396

3 Claims. (Cl. 244—155)

1

The present invention relates to a traveler or carrier attachment for kites and, more particularly, to a carrier attachment adapted to travel up a kite string to a predetermined point and then release a toy parachute which will float gradually to the ground.

An important object of the present invention is to provide a novel releasing mechanism which will automatically release the toy parachute from the carrier at a predetermined point on the kite string, said mechanism being easy to set and operate.

Another object of the present invention is to provide a carrier for releasing a toy parachute at a predetermined point on a kite string which may be easily and inexpensively manufactured.

A still further object of the present invention is to provide a carrier for attachment to a kite string which will release a parachute at a predetermined point on the kite string that will be stable in its travel along the kite string so that the releasing mechanism will not be prematurely released.

A further object of the present invention is to provide a carrier attachment for travel along a kite string which may be manufactured with a minimum of moving parts from plastic material or the like.

These and other objects of the invention are obtained by the novel construction and arrangement of parts disclosed in the specification, claims and the accompanying drawings, in which:

Figure 1 is a perspective view illustrating the application of the present invention to a kite string;

Figure 2 is a side elevational view of the carrier showing the releasing mechanism in the released position;

Figure 3 is a top plane view of the carrier;

Figure 4 is a front elevational view of the carrier with the releasing mechanism in the unreleased position; and

Figure 5 is an enlarged, fragmentary side elevational view of the released mechanism of the carrier in the unreleased position.

Referring to the drawings, wherein like characters or reference numerals represent like or similar parts, and more particularly, referring to Figure 1, a kite 10 is shown attached to a kite string 12 upon which is mounted the carrier or traveler 14 of the present invention. Carrier 14 supports a toy parachute 16 having a toy figure 18 attached thereto by means of the shrouds or harness 20. As is well known in the art, the toy figure 18 must be made of a heavy material so

that the parachute will descend properly to the ground, after its release from the carrier 14. The carrier 14 will travel up the kite string 12 by wind catching in and pulling the open parachute 16 until the releasing mechanism of the carrier strikes an abutment 22 on the kite string. Abutment 22 may be a knot in the kite string or a stop rigidly mounted on the kite string. At the predetermined point of release on the kite string, the releasing mechanism will be actuated to release the parachute and allow it and the toy figure to descend or float gradually to the ground.

As shown in Figure 2, the carrier 14 consists of a flat, elongated body 24 having kite string-engaging hooks 26 extending from the upper longitudinal edge of the body at each end thereof. Kite string-engaging hooks 26 are oppositely disposed, so that the kite string 12 may pass therethrough but will not become easily disengaged from the hooks 26 while carrier 14 is traveling up the kite string. The elongated body 24 is preferably made from a flat piece of plastic material, but it is within the contemplation of the invention that the body may be made from other materials, such as sheet metal or the like. Elongated body 24 is streamlined in configuration so that it will be lighter and more pleasing to the eye.

The releasing mechanism for releasing a ring 42 attached to the harness or shrouds 20 and supporting the toy parachute and figure, consist of a slotted member 28, a slightly resilient member or arm 30 and a latch plate or retaining element 32. Slotted member 28 is attached to the lower longitudinal edge of the elongated body 24 at the forward end thereof and extending downwardly and forwardly therefrom. Resilient arm 30, which is also attached to the lower longitudinal edge of the elongated body 24 but to the rear of the slotted member 28, extends downwardly and forwardly from body 24 to a point adjacent the end and below the slotted member 28. The free end of the resilient arm is notched, as shown at 40, for reasons which will be more apparent later in the specification. As is apparent from the drawing, slotted member 28 and resilient arm 30 are made integral with elongated body 24, but it is within the scope of the invention to make these units separate and to rigidly attach them to the elongated body. Latch plate or retaining element 32, which holds ring 42 on resilient arm 30, has a curved bifurcated end 34 adapted to receive the kite string therebetween and to engage the abutment or stop 22. At the other end of the latch plate or retaining element 32 there is a pair of openings 36 separated by a cross bar 38. The

openings 36 are adapted to receive and frictionally hold the slotted member 28 and the aforementioned cross bar 38 acts as a pivot point upon which the latch plate 32 will pivot in the slot of the slotted member 28. The lower opening 36' of the pair of openings 36 is also adapted to receive the notch 40 of the resilient arm 30 when the carrier is in the unreleased or set position, as shown in Figure 5.

It is now evident that, when the latch plate 32 is pivoted to the position shown in Figure 5 and the resilient arm 30 is spring-pressed into position in the lower opening 36 of the latch plate and held there by the notch 40 bearing against the wall of the opening 36', that the ring 42, attached to the parachute harness 20, will be retained in place on the resilient arm 30. As the wind, which supports the kite, also carries the parachute 16 and the carrier 14 up the kite string 12, the ring 42 will remain in position until the bifurcated portion 34 of the latch plate 32 engages the abutment 22 on the kite string. At this point, the latch plate 32 will pivot free of the resilient arm 30 and the ring 42, supporting the parachute 16 and toy figure 18, will slide down the arm 30 and be released therefrom so that the parachute may descend gradually to the ground.

In order that the carrier or traveler 14 will be more stable as it travels up the kite string 12, and in order that the carrier will assume the appearance of an airplane, a pair of wings 44 are provided. The wings 44 extend from each side of the elongated body 24 and will help to maintain the body stable as the carrier is moving up the kite string.

It is now apparent that we have developed a new and novel traveler or carrier for releasing a parachute at a predetermined point on a kite string. It is evident that the carrier may be manufactured by molding from plastic material and that it consists of only two separate parts, namely, the carrier body 14 with its integral hooks 26, slotted member 28 and resilient arm 30, and the latch plate or retaining element 32.

The terminology used in the specification is for the purpose of description and not for limitation, the scope of the invention being defined by the appended claims.

We claim:

1. A carrier of the type adapted to travel along a kite string and release a toy parachute at a predetermined point, comprising a flat, elongated body, kite string-engaging hook means extending from the upper longitudinal edge of said body at each end thereof, a slotted member extending downwardly and forwardly from the lower longitudinal edge of said body, a resilient arm adjacent and to the rear of the slotted member and extending downwardly and forwardly from said body, and a retaining element for holding the parachute on said resilient arm, said retaining element being bifurcated at one end thereof for engagement with an abutment on the kite string at the predetermined point of release, and having at the other end thereof an element pivotally mounted in the slot in the slotted member and a

second element releasably engaging said resilient arm.

2. A carrier of the type adapted to travel along a kite string and release a toy parachute at a predetermined point, comprising a flat, elongated body, kite string-engaging hook means extending from the upper longitudinal edge of said body at each end thereof, a slotted member extending downwardly and forwardly from the lower longitudinal edge of said body, a resilient arm adjacent and to the rear of the slotted member and extending downwardly and forwardly from said body, said resilient arm having a notch in the free end thereof, and a retaining element for releasably holding the parachute on said resilient arm, said retaining element being bifurcated at one end thereof for engagement with an abutment on the kite string at the predetermined point of release, and having at the other end thereof a pair of openings separated by a cross bar to receive said slotted member for pivotal engagement therewith, and the lower of said openings releasably engaging the notch of said resilient arm, whereby the toy parachute is retained on said resilient arm until said retaining element contacts the abutment on the kite string and pivots free of the resilient arm.

3. A carrier of the type adapted to travel along a kite string and release a toy parachute at a predetermined point, comprising a flat, elongated body, kite string-engaging hook means extending from the upper longitudinal edge of said body at each end thereof, wing-shaped members extending from each side of said body for stabilizing said carrier during the travel along the kite string and at the releasing point of the toy parachute, a slotted member extending downwardly and forwardly from the lower longitudinal edge of said body, a resilient arm adjacent and to the rear of the slotted member and extending downwardly and forwardly from said body, said resilient arm having a notch in the free end thereof, and a retaining element for releasably holding the parachute on said resilient arm, said retaining element being bifurcated at one end thereof for engagement with an abutment on the kite string at the predetermined point of release and having at the other end thereof a pair of openings separated by a cross bar to receive said slotted member for pivotal engagement therewith, and the lower of said openings releasably engaging the notch of said resilient arm, whereby the toy parachute is retained on said resilient arm until said retaining element contacts the abutment on the kite string and pivots free of the resilient arm.
